UNITED STATES PATENT OFFICE.

NEWTON FLOYD THOMAS, OF JASPER, TENNESSEE.

IDENTIFICATION-TAG.

1,272,573.

Specification of Letters Patent. Patented July 16, 1918.

Application filed March 5, 1918. Serial No. 220,571.

To all whom it may concern:

Be it known that I, NEWTON F. THOMAS, a citizen of the United States, residing at Jasper, in the county of Marion and State 5 of Tennessee, have invented a new and useful Identification-Tag, of which the following is a specification.

The device forming the subject matter 10 of this application is an identification tag adapted to be carried by soldiers and others and the invention aims to provide a tag which will be practically indestructible, being subject to deterioration neither by moisture nor by the application of fire or excessive heat.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described 25 and claimed, it being understood that changes in the precise embodiment of the invention disclosed can be made within the scope of what is claimed without departing from the spirit of the invention.

In the accompanying drawings:—

Figure 1 shows in elevation, a device constructed in accordance with the present invention;

Fig. 2 is a cross section on the line 2—2 of Fig. 1;

Fig. 3 is an elevation of the tag proper removed from its sheath; and

Fig. 4 is a sectional detail illustrating a modification of the invention.

In carrying out the present invention there is provided a water-proof transparent container 1, preferably made of glass, and of but little thickness. Disposed within the container 1 is a tablet 2 made of a refractory and fire-proof material, mica being used ordinarily. The tablet 2 is sealed hermetically in the container 1, and, since the tablet is of refractory material, the glass which

forms the container 1 may be fused across the edge of the tablet, thereby inclosing the 50 tablet completely in glass, although any other suitable means for sealing the tablet hermetically in the container may be provided.

An inscription of any desired kind is 55 made on the tablet 2. Preferably, the constituent material of the tablet is altered mechanically to fashion the inscription, and, if desired, the tablet can be perforated, as shown at 3 to fashion the inscription. 60

Since the tablet 2 is completely inclosed in the glass container 1, the tablet will not deteriorate due to the presence of moisture. If the structure is subjected to heat or fire, working a destruction of the glass container 65 1, the fire-proof tablet 2 still will remain intact, its inscription 3 being discernible.

It will be obvious that a body whereon is found a tag constructed in accordance with the invention, may be identified, even 70 though it has been subjected to a downpour of rain or to a fire which has swept the battlefield or ship whereon the wearer has fought.

The tag shown in Fig. 3 may be carried 75 in the pocket or otherwise. If desired the tag may be placed in a sheath 4 fashioned like an envelop and provided with slits 5 defining ribs 6 through which is passed a belt 7. The belt 7 may be withdrawn and, 80 if desired, the tag, contained within the sheath, may be carried within the pocket.

The device may take forms other than that shown in Fig. 3, thus, in Fig. 4 is shown a container 8 fashioned as above described, 85 inclosing a tablet 9 of the sort hereinbefore alluded to, the container having a stick pin 10, the device thus being in the form of a button or badge.

If desired, a photograph or any other 90 relatively thin object can be placed in the containers 1 or 8.

What is claimed is:—

1. An identification tag embodying a hermetic transparent water-proof container; 95 and a refractory fire-proof tablet within the

container, the constituent material of the tablet being altered mechanically to fashion an inscription.

2. An identification tag embodying a hermetic transparent glass container and a mica tablet in the container, the constituent material of the tablet being punched to fashion an inscription.

Copies of this patent may be obtained for five cents each, by addressing the "Commissioner of Patents, Washington, D. C."

In testimony that I claim the foregoing as my own, I have hereto affixed my signature in the presence of two witnesses.

NEWTON FLOYD THOMAS.
